CLAIM

The ornamental design for a theater-chair-supported
seat, as shown and described.

DESCRIPTION

FIG. 1 is a bottom perspective view of a theater-chair-supported
seat showing my new design;

FIG. 2 is a bottom plan view thereof;

FIG. 3 is an end elevational view thereof;

FIG. 4 is a top plan view thereof;

FIG. 5 is a side elevational view thereof; and,

FIG. 6 is an end elevational view, showing the end
opposite of that shown in FIG. 3.

FIG. 1

FIG. 2

FIG. 3
